PASTING MACHINE

Solomon Caufman, New York, N. Y.

Application January 31, 1941, Serial No. 376,815

6 Claims. (Cl. 216—20)

This invention relates to a machine for pasting textile fabrics and the like to a table top or other suitable surface preparatory to screen printing on the surface thereof.

An object of this invention is the provision of a simple mechanism by means of which the surface to which a textile fabric is to be cemented or pasted in preparation for the printing of designs thereon may be uniformly covered with a thin layer of cement or paste evenly spread on the surface thereof.

A further object of the invention is the provision in the same machine of means for supplying the textile fabric to the surface, applying it smoothly thereon, pressing it down onto the surface under proper tension.

Another object of the invention is the provision in the same machine of a heated pressure roller for insuring smooth application of the textile fabric to the table top and quickly drying the paste adhesive.

A still further object of the invention is the provision in the same machine of either a spray device for applying the cement or paste to the surface, or a feed roller for the same purpose.

Another object of the invention is to provide in the same machine means for spreading the paste after it is applied to the table top and for removing the excess thereof just before the application of the textile fabric thereto.

A still further object of the invention is the provision of means for supplying clean water to the table top after the printed fabric is stripped therefrom, and for thoroughly removing the paste therefrom in preparation for the next application of fabric thereto.

Other and more detailed objects of the invention will be apparent from the following description of one embodiment thereof when taken in connection with the attached drawings.

This invention resides substantially in the combination, construction, arrangement and relative location of parts as will be described in detail below.

In the accompanying drawings,

Figure 1 is a side elevational view of one embodiment of this invention;

Figure 2 is a top plan view thereof;

Figure 3 is an end elevational view of a portion of the machine showing a modified form of mechanism for applying paste to the table top to be used particularly with light weight fabrics such as rayons, crepes, voiles, and the like;

Figure 4 is a cross-sectional view through this modified arrangement;

Figure 5 is a top plan view of a portion of the machine showing a modified form of cleaning device for removing the paste from the table top;

Figure 6 is a right hand elevational view of this mechanism; and

Figure 7 is an end elevational view with some parts in section and some parts broken away of a modified form of pressure member.

In the printing of textile fabrics of various kinds, and especially in the screen printing thereof, in accordance with this invention, suitable lengths of the fabric are cemented to a table top and the desired design is applied thereto by printing, preferably by the screen printing method. The cement or paste is applied to a table top, which is surfaced with oil-cloth, and the fabric is then placed down on the cement or paste, all by the same machine.

By the prior practice these operations were carried out by hand and the fabric after being stretched and smoothed is fastened in place by pins. This is a slow, tedious time consuming and difficult operation. The invention herein disclosed provides in a simple mechanism means for applying cement or paste to the oilcloth surface of the table top in the proper quantity and properly distributed, and then applying thereover the fabric in a stretched smooth condition followed by the pressing of the fabric into intimate contact with the moist cement or paste, and the drying thereof, all in a simple operation. After the fabric is printed it is stripped from the table surface, which when cleaned is ready for the next application of fabric thereto.

A description of an embodiment of the invention as herein disclosed for the purposes of illustration will now be set forth in full detail. A table or support 1 suitable for the purpose is provided with a pair of rails 2 lying in parallel relation to each other and to the table sides as clearly shown in Figure 2. The area of the table top between the rails is surfaced in any suitable manner as by means of a layer of oilcloth 3, as is commonly used in this art. A carriage is longitudinally moved on these rails and consists of a pair of suitably shaped side frame members 4 cross connected by rods 5 uniting them into a self-supporting movable carriage. The carriage is provided at its corners with suitable flanged wheels 6 rotatably mounted thereon and positioned to engage the rails 2 to permit ready transport of the carriage longitudinally of the rails. Movement of the carriage over the rails is caused by means of a hand crank 54 which is

connected to a gear 53 journaled on one of the side frame members 4 and meshing with another gear 52 secured to the axle to which the wheels 6 at the adjacent end of the carriage are mounted. Thus, by turning the crank 54 the carriage and all parts mounted thereon may be caused to move back and forth on the rails.

On the upper part of the carriage is journaled a shaft 7 on which a roll 8 of the fabric to be treated may be mounted so that the fabric may be readily unreeled from the roll. The fabric extends from the lower surface of the roll as shown in Figure 1, to and around a drum or roller 9 mounted upon a shaft 10 journaled in bearings at one end of the carriage as shown. Mounted on the shaft 10 is a double ended lever 11 having one arm bifurcated, which together with the tightening bolt 12 acts as a clamp to vary the resistance to rotation of the roller 9. The other arm of lever 11 engages a stop 13 on the carriage. With this arrangement it will be seen that the resistance to rotation of the roller 9 can be varied by tightening or loosening the bolt 12. The fabric extends from the roll 9 to a freely rotatable expansion roll 14 journaled on the carriage, and after passing therearound extends down to the surface of the table 1. The surface of the expansion roll 14, in accordance with well known practice in this art, is provided with a suitable design of a nature which tends to expand and stretch the goods axially thereof while it engages therewith. In the case of heavy fabrics a stationary expanding device may be employed having a suitably configurated surface to cause the transverse stretching of the goods as it moves thereover. This is likewise in accordance with knowledge in this art.

A heated pressure drum 15 is journaled on the carriage as shown by means of a shaft 17, which is rotatably mounted in journal blocks 18 slidably mounted for vertical movement in the carriage frame. A spring 19 is interposed between the journal block 18 and the frame, and a screw 20 engages the top of the journal block so that the vertical position of the drum 15 may be adjusted. The bearing construction for this drum at the other side of the carriage is the same as that shown in Figure 1 and just described. The surface 16 of the drum 15 is preferably covered with or made of a suitable metal such as copper. The roller 15 is in reality a closed drum that may be heated in any one of a number of suitable ways well known in this and related arts. The means for heating the roller is not disclosed since it is unnecessary to an understanding of the invention. The drum may be heated by steam, hot water, electric heating elements, or by any way suitable for the purpose.

Mounted on upwardly extending brackets 21 on a shaft 23 is an elongated clamp support 22 for the doctor blade 27 which is held therein by means of a number of set screws 28. The lower end of the doctor blade 27 is preferably covered with a replaceable felt facing 29. Mounted on the shaft 23 is a cam 24 which engages with a cam operator 25 connected to a pivotally mounted hand lever 26. By operating the hand lever 26 in a clockwise direction the doctor blade 27 may be moved to disengage its felt covered edge from the table top.

A similar bracket 30 is mounted on each side of the frame of the carriage and journaled therein on a shaft 32 is another doctor clamp 31 in which the doctor blade 36 is secured by means of the set screws 37. The lower edge of the doctor

blade 36 is covered with a rubber facing 38. A cam 33 secured to the shaft 32 cooperates with the cam operator 34 connected to the hand lever 35 pivotally mounted on the bracket 30. By clockwise rotation of the hand lever 35 the doctor blade 36 may be raised out of engagement with the table top. As is illustrated in the drawings the doctor blade supporting clamps are preferably made relatively massive so that the weight thereof will act to force the doctor blades into contact with the table surface under the necessary pressure. If desired these clamps may be constructed to receive weights, not shown, or suitable springs, not shown, may be supplied to accomplish the same object with more flexibility.

Mounted on the carriage at some suitable point, as for example at the end as indicated in Figure 1, is a container 38 having a removable cover 39 and a transverse partition 40 dividing it into two compartments. For the sake of description it will be assumed that the left hand compartment, Figure 1, is to contain clean water and the right hand compartment the paste or cement. The right hand compartment is provided with a discharge connection 41 having a valve 42 therein, which connection extends to the intake port of a suitable pump 43. This pump has a drive pulley 44 which is connected by a belt 45 to the pulley 46 of a suitable driving motor 47, illustrated as an electric motor. The output part of the pump is connected by a pipe 48 to a spray head 49, which is in the form of a long tube extending across the machine and mounted on the side frames as shown in the figures. The lower wall of the spray head 49 is provided with suitable openings either in the form of a long narrow slit, or a plurality of small holes so that when the fluid cement or paste is supplied thereto under pressure it will spray it onto the oilcloth surface 3 of the table throughout the width thereof in suitable quantities. When the carriage is caused to traverse the table, say from left to right, and with the spray in operation, the entire oilcloth surface is covered with a layer of cement or paste in suitable quantities. During these operations the valve 42 is opened. To complete the structural description it will be noted that the left hand compartment is connected by a pipe 50 to the intake of the pump 43 and is provided with a valve 51 which would be closed during the pasting operation. During the cleaning operation to be described later, valve 51 is opened, and valve 42 is closed, so that fresh water may be sprayed onto the oilcloth surface.

In the printing of light weight fabrics such as rayons, crepes, voiles, and the like, it is preferable not to use the spraying apparatus for pasting the oilcloth surface. For the preparation of these fabrics for printing a different mechanism is provided for applying the paste. This is shown as comprising a smooth roller 55 journaled in the carriage so that the surface thereof will engage the oilcloth surface and be caused to revolve when the carriage is moved along the rails. The roller 55 engages a similar roller 57 which is rotatably mounted and which in turn engages a similar roller 58. The roller 58 is supported so that its lower surface is submerged in the pasting material mounted in the trough 59. An adjustable scraper blade 60 engages the surface of the roller 58 to scrape off the excess pasting material which is carried up by the roller as it revolves, so that it may run back into the contain-

er 59. The thin layer of paste which passes by the scraper is transferred to the roller 57 and by it to the surface of the roller 55. The roller 55 applies this pasting material in a thin layer over the entire width of the oilcloth surface. It will be noted that for the sake of ease in operation the bracket 56 and all the parts connected thereto, including the rollers 55, 57 and 58 and the container 59, may be mounted on the carriage in any number of obvious ways in order to raise the roller 55 out of contact with the oilcloth surface 3 when this part of the mechanism is not being used. Such raising mechanism is not disclosed since many ways of accomplishing this will be apparent to a skilled mechanic.

The operation of the machine will be more or less apparent from the above description, but a brief repetition thereof seems desirable. It will be assumed that the oilcloth surface 3 is clean. In order to paste a particular fabric thereon the end thereof is passed from the supply reel 8 around the tension roller 9, the expansion roller 14, and from there down to the oilcloth surface. The carriage is caused to move from left to right with the spray head 49 in operation a sufficient distance so that the heated pressure roller 15 is adjacent the beginning of the pasted area. In moving the carriage to this point the covered doctor 36' being in its lower position will operate to insure a uniform distribution of the paste over the oilcloth surface and the felted doctor 27 following the action of the rubber covered doctor 36 will act to remove any excess paste. The result is that at the point of application of the end of the fabric strip to the table top there is a thin uniformly distributed layer of paste in just the right quantity. The terminal end of the fabric is placed in engagement with the pasted surface in proper position, and the carriage is then again moved to the right by means of the crank 54, so that the heated pressure roller 15 passes over the adjacent end of the fabric and from then on rolls the fabric under pressure and the proper tension into intimate contact with the pasted surface. The roller being heated, the paste is quickly dried. The pressure of the roller 15 on the surface can be adjusted by means of the screws 20 so that at the tail end of the travel of the carriage to the right the working surface of the table will have pasted thereto in a smooth layer fabric about to be printed. The paste will have been dried by the heated pressure roller, and the fabric surface will be smooth and taut, that is it will be in the proper condition for further treatment such as screen printing.

The action of the tension roller 9 is such as to keep the fabric which is delivered therefrom to the table surface under the desired tension. This tension may be adjusted by varying the gripping action of the lever 11 on the end of the shaft 10. At the end of the travel of the carriage the fabric is cut off and the carriage moved out of the way. After the fabric is printed it is stripped from the oilcloth surface in the usual manner. The carriage then moves back to the beginning of its travel at the left, the paste supply of course having been cut off by stopping the pump and closing valve 42. The doctor blades are removed and in place thereof a rubber covered doctor blade is mounted in the holder 22 and a sponge covered rubber blade is mounted in the holder 31. When these doctor blades contact with the table top and the valve 51 opens the carriage may be removed to the right, and with pump 43 running clean water will be sprayed on the previously

pasted surface. The sponge of the leading doctor will serve to wipe the surface and absorb much of the water with the dissolved paste. The trailing rubber covered doctor will squeegee the surface, removing any remaining moisture. The table is then ready for repasting for reuse as before.

In the treatment of lighter weight materials where it is desirable to use less cement or paste, the drum paste applier is used. In this case the spray head 49 is not used. The drum paster is moved down so that the roller 55 contacts the oilcloth surface with a suitable cement or paste in the container 59 when the carriage is moved from left to right. The drum pasting equipment, as previously described, will apply a thin uniform layer of paste to the oilcloth surface. The doctor blades 27 and 36 can be used, if desired, to further insure spreading of the paste or cement and the removal of excess thereof. However, they may be raised out of contact with the table surface, and not used in this case. The lighter fabric is mounted on the shaft 7 and supplied as previously described. The heated pressure roller 15 is, of course, used to roll the fabric onto the pasted surface and dry the paste as before.

A modified form of pasting arrangement equivalent to that including the roll 55 and associated equipment is illustrated in Figures 3 and 4. In other words, the mechanism of Figures 3 and 4 may be employed when for any reason it is not desirable to use the spray paster. As shown in these figures, removable brackets 55^a are mounted on the frames 4. Journaled in these brackets is a roll 55 having a smooth surface or finely engraved so as to apply the paste uniformly to the oilcloth surface 3. A tank 59' for the paste of suitable form and co-extensive axially with the roll 55' is also mounted on the brackets 55^a. The bottom of this tank is bent and is of proper shape so as to fit snugly against the periphery of the drum 55. This arrangement is particularly useful where the pastes are not too thin and are of a consistency so that there is little tendency for it to leak out of the container. A pivotally mounted doctor blade or scraper 60 is held in engagement with the roll 55' by means of a spring 61 so as to scrape off the excess paste before it reaches the oilcloth surface 3. As will be apparent, the roll 55' rotates in a counterclockwise direction so that its pasted surface is first scraped before it contacts the surface 3. A suitable receptacle 62 is provided to collect the excess paste or cement scraped from the roll 55'. In cases where mechanism of this type is preferred, it may be easily substituted in the machine of Figure 1 by removing the brackets 56 and associated parts. The mechanism of Figures 3 and 4 is preferably used when pasting heavier fabrics to the table top, in which case the multiple roller type of paster is not necessary.

Figure 5 illustrates a wiping or cleaning roller which likewise may be substituted in the machine for the roll pasting mechanism after the oilcloth surface has been pasted a number of times, and therefore needs a thorough cleaning. This roll or drum is illustrated at 65 and is shown provided with a plurality of spirally shaped wiping blades 66 composed of strips of suitable material such as sponge, rubber and the like. One of the detachable supporting brackets for the roll 55 is provided as shown with an expansion arm 69 on which is freely mounted the rotatable idler gear 68. This meshes with a similar gear 67 secured

on the end of the shaft integral with the drum 65. The parts are proportioned so that the idler gear 66 will mesh with the previously described gear 63 to which is attached the handle 54. When the oilcloth surface needs a thorough cleaning the mechanism of Figure 5 may be substituted in the machine, and as the carriage is moved along by turning handle 54 the wiping blades of the drum 65 are caused to revolve against the direction of movement of the carriage and at a sufficiently relatively rapid rate so that the wiper blades 66 scrub and clean the oilcloth surface 3. Thus this device aided by the doctor blades as previously described, will serve to thoroughly clean the oilcloth surface. By this time, of course, the spray head 48 sprays clean water onto the oilcloth surface.

In passing it may be noted that in the handling of some goods the paste is of such consistency that it is not necessary to spray it. In this case the motor driven pump may be dispensed with, or the pump may be by-passed so that the paste may be allowed to flow by gravity to the spreader or spray head 48, which in this case might be modified so that its apertures will permit the right amount of paste to flow therethrough by gravity.

In place of the heated pressure roller 15 there may be mounted on the carriage 4 a heated ironing member 15' of sufficient weight for pressing the fabric onto the pasted table top 3. The iron is preferably provided with a pointed nose 15^a quite similar to other well known forms of pressing irons. The iron is heated in any suitable manner, as for example as illustrated by means of electrical heating coils enclosed therein and provided with the current supply leads L. There is not shown, but it will be apparent to those skilled in the art, that different types of construction may be employed for adapting the iron for mounting in the carriage 4, including, as illustrated in the case of the roller 15, means for varying the pressure of the iron on the fabric as it presses the fabric onto the pasted table top. Transversely of the machine the iron will, of course, extend a sufficient distance so as to be at least as wide as the fabric to be pasted down.

From the above description it will be apparent to those skilled in the art that the single embodiment of the invention herein disclosed for the purpose of illustrating the principles of this invention may be varied in many obvious ways without departing from the novel scope of the subject matter herein disclosed. I do not, therefore, desire to be limited to the disclosure as given for purposes of illustration, but rather to the scope of the claims granted me.

What is claimed is:

1. In a machine for applying a web to a pasted surface, the combination including a movable carriage, a heated pressure roller mounted on said carriage, means for supplying a web under tension to the pressure roller, means mounted on the carriage for supplying a paste to the surface to which the web is to be pasted in advance of the heated pressure roller in the direction of movement of the carriage, and means for spread-

ing the paste on and removing the excess thereof from the surface to be pasted.

2. In a machine for applying a web to a pasted surface, the combination including a movable carriage, a heated pressure roller mounted on said carriage, means for supplying a web under tension to the pressure roller, spray means mounted on the carriage for supplying a paste to the surface to which the web is to be pasted in advance of the heated pressure roller in the direction of movement of the carriage, and means for spreading the paste on and removing the excess thereof from the surface to be pasted.

15 3. In a machine for applying a web to a pasted surface, the combination including a movable carriage, a heated pressure roller mounted on said carriage, means for supplying a web under tension to the pressure roller, roller means mounted on the carriage for supplying a paste to the surface to which the web is to be pasted in advance of the heated pressure roller in the direction of movement of the carriage, and means for spreading the paste on and removing the excess thereof from the surface to be pasted.

20 4. In a mechanism of the type described, the combination including a surface to which a fabric web is to be pasted, a carriage longitudinally movable with respect to said surface, a heated pressure roller mounted on said carriage so as to engage said surface, means for supplying a web under tension between the surface and said pressure roller, means for applying a uniform layer of paste to the surface in advance of said pressure roller in the direction of movement of the carriage, and a pair of positionable doctor blades mounted on the carriage having means for moving the doctor blades into and out of engagement with said surface.

25 5. In a machine of the type described the combination including a surface to which a fabric is to be pasted, a carriage mounted for movement longitudinally of said surface, a pressure roller mounted on said carriage so as to engage said surface, means mounted on said carriage for 40 supplying a web under tension to said surface between it and said pressure roller, means mounted on said carriage in advance of said roller in the direction of movement of the carriage for applying paste to said surface as the carriage is moved, a felted doctor blade mounted on said carriage, a rubber covered doctor blade mounted on said carriage in advance of said felted doctor blade, and means for independently moving said doctor blades into and out of engagement with said surface.

45 6. In a machine for pasting a web to a surface, the combination including a supporting means to provide a surface to be pasted, a carriage supported for guided movement longitudinally of 50 said support, a heated pressure roller mounted on said carriage so as to engage said surface with pressure, means for supplying a web under tension between the pressure roller and said surface, means for applying paste to the entire surface of said supporting means in advance of said pressure roller and means for removing the excess thereof from the surface to be pasted.

SOLOMON CAUFMAN.
